INVENTOR
CURTIS T. CLIFFORD

BY

John H. Miller
ATTORNEY

UNITED STATES PATENT OFFICE.

CURTIS T. CLIFFORD, OF SAN FRANCISCO, CALIFORNIA.

SPRINKLER HEAD.

Application filed February 24, 1919. Serial No. 278,620.

To all whom it may concern:

Be it known that I, CURTIS T. CLIFFORD, a citizen of the United States, and a resident of the city and county of San Francisco, 5 State of California, have made a new and useful invention—to wit, an Improved Sprinkler Head; and I hereby declare the following to be a written description of the same in such full, clear, concise, and exact 10 terms as to enable any person skilled in the art to which it apertains or to which it is most nearly connected to make, construct, and use the same.

The present invention is an improved 15 sprinkler head and relates more particularly to bonding links for sprinkler heads.

The primary object of the invention is to provide a composite link member, adapted to yieldably retain toggle members commonly 20 employed in sprinkler heads of automatic fire extinguishers, and provided with means interposed between the component members of the bonding link for spreading the said members of the link when the fusible solder 25 is melted.

In many instances the bonding links of 30 sprinkler heads now in use have failed in operation at critical times because of the fact that the fusible solder used as a seal for the link at the moment of fusing and parting 35 movement of the plate members of the link, becomes cooled from air or water under pressure escaping from the partly released disc valve, and again bonds the plate members, thereby failing to completely release the 40 valve.

My invention contemplates a leverage 45 means for spreading the plate members of the bonding link which will positively part the said plates at the time the solder is fused and obviate the possibility of any particles of the fusible metal again bonding the plates.

In this specification and the annexed 50 drawings, I illustrate the invention in the form which I consider to be the best, but it is to be understood that I do not limit myself to such form because the invention may be embodied in other forms, and it is also to be understood that in and by the claims following the description herein I desire to cover the invention in whatever form it may be embodied.

In the accompanying one sheet of drawings:

Figure 1 is a side elevation of a typical

sprinkler head with my invention installed thereon.

Fig. 2 is an elevation of the same taken transversely to that of Fig. 1, and looking in 60 the direction of the arrow in Fig. 1.

Fig. 3 is a plan view of a bonding link plate.

Fig. 4 is an edge view of the same.

Fig. 5 is a plan view of the other link 65 plate.

Fig. 6 is an edge view of same.

Fig. 7 is a side elevation of a spreading element.

Fig. 8 is an end view of the same. 70

Fig. 9 is a vertical central sectional view on a larger scale, showing the members of the bonding link in locked relation.

Fig. 10 is a similar view illustrating the direction of pull applied to the plate members 75 of the bonding link by the water pressure when the fusible metal has melted, and the effect of the spreader relative to the plates.

Fig. 11 shows in detail the form of one of 80 the plate members of the bonding link.

Fig. 12 is a side elevation of two plate members of modified form.

Referring to the drawings, the structure here shown comprises a nozzle 1 threaded as 85 shown at 2 for attachment to a water conveying system, and adapted to be sealed by the flat disc valve 3. Integral with the nozzle 1 and rising therefrom is a looplike frame 4 terminating at the top in a boss 6 90 opposite the valve disc 3 and coaxial therewith.

Supported by the boss 6 and threaded into it is the stem of a water distributer 7, the lower threaded end of which pivotally engages 95 one end of an elbow lever 8 which engages a similar elbow lever 9 pivoted at one end on the disc valve 3.

The elbow levers 8 and 9 are in reverse relation and have divergent arms terminating 100 in opposed hooks 11 and 12. The elbow levers 8 and 9 form a toggle joint adapted to securely hold the disc valve 3 seated.

The elbow lever 8 is provided with a wedge like tongue 13 which engages a 105 groove 14 in the lever 9.

In assembling the sprinkler head the toggle joint is purposely placed out of alignment with the axial line of the distributer 7 and disc valve 3, so that the pressure in 110 the nozzle or the resiliency of the sprinkler frame 4 will collapse the entire structure of

the bonding link and unseat the valve 3 causing the water to be disseminated by the distributor 7.

The parts which have been so far described are not in themselves new and form no part of the present invention although they bear a cooperative relationship to the novel elements hereinafter described.

The toggle members 8 and 9 are held in the position shown in Figs. 1 and 2 and the collapse of the structure prevented by a composite link composed of two plates 16 and 17 and an interposed spreader element or angle bar 18.

15 The plates 16 and 17 may be struck from blank metal or cast or pressed as desired. Each of the said plates is bifurcated on one end as shown at 19, 21 to form a clearance respectively for the hooks 11 and 12, and 20 each is also provided with a hole as shown at 22, 23 for engaging respectively the hooks 11 and 12.

25 The plate 16 is provided with a groove 24 adapted to engage one horizontal member or flange of the angle bar 18 while the plate 17 is provided with a wider, more shallow groove 26 adapted to snugly enclose the vertical member or flange of the said angle bar 18, as shown in Figs. 1 and 9. This 30 construction permits the assembly of the component parts of the bonding link in the compact vertical alignment shown in Fig. 1 in which position they are secured by a sufficient quantity of fusible solder adapted 35 to fuse at a temperature approximating 165 degrees.

When the solder is melted, the screw 40 stress at toggle member 8 and pressure in the nozzle against the disc valve tends to spread the toggle members 8 and 9 of the toggle joint and exerts a pull in opposite directions on the plates 16 and 17 secured respectively to hooks on arms 8 and 9. These opposed forces cause the angle bar 45 18 to heel over as shown in Fig. 10 and act as a wedge spreading apart the said plates 16 and 17 which because of its angular shape prevents the plates 16 and 17 from returning to a contact position and the possibility of again becoming bonded, thus 50 insuring collapse of the entire link structure and releasing the disc valve 3.

It is obvious that at the slightest movement of the plates 16 and 17 in the direction 55 indicated by the arrows in Fig. 10 the interposed angle bar immediately becomes effective as a spreader and it will be impossible for any particles of the fusible metal to adhere or cohere to abort the operation of 60 the device.

In Fig. 11 I have shown an enlarged view 65 of the plate 17 in which the groove 26 is provided with a projection having oblique faces 28—29 meeting at a point 31. This construction facilitates the movement of the

member 18 and as the fulcrum point 31 engages the said member 18 the cut away portion 28 affords clearance for the member 18 when in the position shown in Fig. 10.

I do not limit myself to the construction 70 of plate 17 as shown in Fig. 11 as the same object can be obtained by a slight offset in both plates 16 and 17 away from the sheer line thus producing an off-center pull on angle bar 18 as shown in Fig. 12.

Having thus described my invention, what I wish to secure by Letters Patent is:

1. A sprinkler head link constructed of two plate members each having a transverse groove at right angles to the proximate faces of the plates and constructed to conform one with one leg and the other with the other leg of an angle bar, and an angle bar disposed in the slots so formed. 80

2. A sprinkler head link constructed of two plate members each having a transverse groove at right angles to the proximate faces of the plates and constructed to conform one with one leg and the other with the other leg of an angle bar, and an angle bar 90 disposed in the slots so formed, and a solder joint between the proximate surfaces of the plates.

3. A sprinkler head link constructed of two plate members each having a transverse groove at right angles to the proximate faces of the plates and constructed to conform one with one leg and the other with the other leg of an angle bar, and an angle bar disposed in the slots so formed, and a solder 100 joint between the proximate surfaces of the plates, said grooves being slightly larger than said angle bar so that the bar will tilt and spread the plates as they are oppositely pulled in the direction of their length when 105 the solder melts.

4. A sprinkler head link constructed of two plate members each having a transverse groove at right angles to the proximate faces of the plates and constructed to conform one with one leg and the other with the other leg of an angle bar, and an angle bar disposed in the slots so formed, and a solder joint between the proximate surfaces of the plates, the opposite end of each member 110 constructed and adapted to be attached to mechanism holding the link in tension and one of the legs of said angle bar being in shear.

5. In a sprinkler head link the combination of two plate members each having a transverse keyway in their proximate faces, the keyway in one of the plates being wider than the keyway in the other plate, an L shaped key adapted to engage loosely within the said keyways, the longer leg of the L and the angle formed by the shorter leg of the L therewith located within the larger keyway of one of the plates, and the remaining portion of the short leg of the key 115 120 125 130 135

- gaging the small keyway in the face of the other plate so that a longitudinal movement of the plates causes the corner of the said key to engage against the inner surface of the larger transverse keyway and the divergent ends of the legs of the key to engage one within the smaller transverse keyway of the other plate and the other against the adjacent surface of the last named plate.
- 10 6. A fusible link comprising two mating plates each provided with means at one end to engage a cooperating part, said engaging ends extending in opposite directions when the parts are assembled, the said plates each 15 having formed therein a depression which when brought into alignment provides a keyway, one of said depressions being of larger area than the other, in combination with a cooperating key on one side formed 20 to loosely seat in the larger depression, and on the other side having a part to loosely seat in the other depression, with a portion of the key at that side lying on the inner face of the plate.
- 25 7. A device of the kind described comprising mating plates each having formed therein a depression which when the parts

are assembled forms a substantially L-shaped key way, in combination with a co-operating L-shaped key formed to loosely seat in the key way, whereby as the plates are moved longitudinally one upon the other the key will disengage from the key way.

8. In a device of the kind described comprising mating plates each being provided with a recess which when the plates are assembled forms a key way, the recess in one plate being longer than the recess in the other plate, in combination with a cooperating key formed to loosely fit within the key way to provide clearance for the ready disengagement of the parts when the plates are moved longitudinally one upon the other, a portion of the key at one side thereof extending beyond the recess in the corresponding plate over the face thereof.

In testimony whereof, I have hereunto set my hand at San Francisco, California, this 15th day of February, 1919.

CURTIS T. CLIFFORD.
